(57) **CLAIM**

The ornamental design for an orthotic with insert as shown and described.

DESCRIPTION

FIG. 1 is an upper perspective view of an orthotic with insert;
FIG. 2 is a side view thereof;
FIG. 3 is a side view thereof;

FIG. 4 is a top view thereof;

FIG. 5 is a bottom view thereof;

FIG. 6 is a front view thereof;

FIG. 7 is a rear view thereof; and,

FIG. 8 is a lower perspective view thereof.

The dashed lines shown in the figures are for purposes of illustrating portions of the orthotic with insert and form no part of the claimed design.

1 Claim, 6 Drawing Sheets
